YARN MEASURING MACHINE

John A. Adell, Orange, Mass.

Application July 1, 1937, Serial No. 151,423

18 Claims. (Cl. 33—132)

This invention relates to a device for measuring thread, yarn, or textile material, in which the machine is stopped automatically after measuring off a certain yardage and is an improvement over my Patent No. 2,043,569, patented June 9, 1936.

The principal objects of this invention are to simplify and reduce the cost of a machine for the same purpose as said patent; to provide a construction in which, when the desired yardage is measured, the machine will stop at zero on a circular scale, thus eliminating some of the difficulty in operating the old machine; to provide a construction in which the whole machine is enclosed in a casing which has no opening through which lint or dust can enter the machine and tend eventually to prevent its operation; to provide an improved arrangement by which the main gear of the machine is operated; to provide in connection therewith improved means for automatically resetting the machine so that, after the thread or yarn is broken after a complete winding operation, the first thing that happens is the automatic turning of a pointer back to the point to which it was set so that on the next operation the same number of yards will be reeled off, and to provide improved means for holding the machine in its stopped position until started again and certain improvements in the means for stopping it.

Other objects and advantages of the invention will appear hereinafter.

Reference is to be had to the accompanying drawings, in which

Fig. 1 is a front view of a preferred embodiment of this invention, with a corner broken away to show the stopping arrangement;

Fig. 2 is a similar view of the inside of the casing showing the clutch but with all parts in the front of the clutch removed and showing a portion of the casing in section;

Fig. 3 is a sectional view on the line 3—3 of Fig. 2;

Fig. 4 is a front view, as indicated by the arrow 4 in Fig. 3, of a rotary member which is operated by the clutch and which operates the main gear and also the resetting arrangement;

Fig. 5 is an edge view of the same as indicated by the arrow 5 in Fig. 4;

Fig. 6 is an outside elevation, as indicated by the arrow 6 in Fig. 1, of a part of the casing showing the connections to the stopping device of the machine;

Fig. 7 is a front view of the dial broken away to show parts behind it;

Fig. 8 is a fragmentary plan of the mechanism for rotating the main gear;

Fig. 9 is a plan of the rotary device for stopping the rotation of this measuring machine;

Fig. 10 is a side view of the mechanism for rotating the main gear;

Fig. 11 is a plan of the parts shown in Fig. 10, as indicated by the arrow 11 in Fig. 10, showing the parts in operating position;

Fig. 12 is a side view of the central shaft, 10 double toothed cam, and manually operated pointer;

Fig. 13 is a side view showing the main pointer, operating gear, and additional features in section;

Fig. 14 is an edge view of the dial plate and rigid plate behind it;

Fig. 15 is a view similar to Fig. 13 showing the complete mechanism between the clutch and the manually operated pointer, most of these parts being shown in section;

Fig. 16 is a plan of a hand setting device;

Fig. 17 is a plan of the parts shown in dotted lines in Fig. 11 and showing the position of all the parts when the main pointer comes back to zero after an operation;

Fig. 18 is a perspective view of the lever 32, and

Fig. 19 is a side view of the lever 32.

As stated, this machine is for the purpose of measuring yarn, thread or fabric and is of the type in which the yarn, or the like, is passed one or more times around a wheel or pulley 10 which, in this instance, is shown as grooved so that the machine may be used for yarn or thread. A different wheel would be used, if it were to measure a fabric. The yarn, thread or fabric is wound or unwound by a winding machine of any well known type, not shown. This operation, of course, rotates the wheel 10 in accordance with the speed of the yarn and therefore the wheel 10 can be considered as the motive power for this measuring machine. In the present instance this wheel is shown as made of such a diameter as to have the circumference a quarter of a yard and one rotation measures a quarter yard.

The wheel 10 is mounted on a shaft 11 in closed bearings on a hollow extension 12 from a circular vertical casing 13. This casing is entirely enclosed and the extension also so that there is no opening for the entrance of lint and dust. On the shaft is a worm 14 which drives a worm wheel 15, as usual. The number of teeth on the wheel 15 controls the number of its rotations relative to those of the shaft 11.

The worm wheel 15 is supported by, but not fixed to, a shaft 16, on which the wheel is freely mounted. This shaft 16 has a bearing in the back of the casing 13. In order to reduce the friction of the wheel 15 against the casing or against a washer or the like, the casing is shown as provided with an annular convex integral projection 17 at the back against which the wheel 15 bears. Thus there is only a small bearing surface and yet the wheel is held against motion backwardly beyond the desired point.

On the other or front side of the wheel 15 is an annular projection 19. Within this projection is a circular clutch disc 20. This clutch disc is perforated at the center so that it will have no bearing on the shaft 16, and is provided with a radial slit 21. Diametrically opposite this slit is a slot 22, shown of circular form, and lined by a spring 22^a so that only a thin piece of metal is left to connect the two halves of the disc beyond this slot. The disc is rendered flexible to that extent. The disc is also provided with another radial slot 23 by which the disc can be turned. Obviously, if some instrument is inserted in the slot 23 and pushed in one direction, that is, the direction away from the nearest wall of the slit 21, it will expand the clutch disc and prevent its turning in the circular space by increasing the friction of the circular periphery of the disc against the wall of the space in which it is located. If it is pushed in the other direction, it will contract the disc, relieve the friction, and the disc can be turned in that direction only. The power is transmitted from the gear 15 through this clutch disc in one direction only.

The parts so far described are shown in my above mentioned patent with the following exceptions:

The casing, including the extension 12, is made dust-proof, that is, there are no openings in it through which dust and lint can enter the casing. This is accomplished without any special features by having the shaft 11 fit a circular hole in the extension to obviate any opening at this point while the shaft does not pass through the extension at the other end. Another feature that is different is the fact that the clutch disc 20 is arranged to rotate in the opposite direction to that shown in the patent. This is for the purpose of permitting the pointer 18 to move along the circular scale on a dial 24 from the point at which it is originally set at the left of the zero point and moved around the scale in a clockwise direction to the zero point and stop, as will appear. The direction of rotation in the patent above mentioned was opposite to this.

On the shaft 16 is fixed an operating disc 25 which has an eccentric pin 26 entering the slot 23. Thus the shaft 16 is directly driven. Therefore, the rotation of this clutch from the shaft 11 will also positively rotate the operating disc 25 but in one direction only. This disc is provided with two teeth 26 and 27 (see Figs. 4 and 5). The tooth 26, once during each complete revolution of the disc, engages a pinion 28 and turns it through the space of one tooth. This pinion is fixed to a shaft 29 which fixedly carries a second pinion 30, which pinion meshes with the circumferential teeth on a main gear 31. Thus the tooth 26 indirectly but positively rotates the pinion 30 and the gear 31 step by step. This gear is fixed to a tubular shaft 31^a freely mounted on the shaft 16. Thus the shaft 31^a is intermittently rotated with the gear 31 operated by the clutch 20.

The shaft 29 (see Fig. 17) with its two pinions, is mounted on a lever 32 which is pivoted on a stud 33 carried on an outer plate 34 which is mounted in stationary position at the front of the casing and fixedly carries the dial 24. This lever 32 is provided with an end 35 against which bears the end of a spring 36 that is wound on the stud 33 and is provided with an arm having a small coil 37 which engages the teeth of the pinion 28 and prevents that pinion from moving more than one tooth at a time and always holds the pinion in place after it has been moved. The lever 32 is provided with two notches 38 and 39 which engage a tooth 40 on a lever 41 pivoted on a stud 42 also carried by the plate 34. Behind the lever 41 is a spring 43 which holds it up so that the tooth thereon will hold the lever 32 by either of the notches 38 or 39 according to the position of that lever. The lever 32 has an arm 44 by which it can be manipulated, as will be seen. The lever 32 has a projection 32^a which will be engaged by a pin 60 on the gear 31 to throw the lever 32 from the position shown in Fig. 11 to that shown in Fig. 17 and the pinion 30 out of mesh with the gear 31.

Up to this point it will be seen that the rotation of the shaft 16 through the clutch 20 will rotate the main gear 31, while in mesh with the pinion 30, constantly but intermittently with a slow motion.

The operating disc 25, as stated, has a tooth or projection 27 which is bent out of the plane of the tooth 26 and at a certain time, as will be described later, engages the arm 44 so as to swing the lever 32 back toward the gear 31 after it has been thrown out of operation and thereby start operation again. The tooth 27 and projection 44 are so located relatively as to contact only when the lever 32 is in a position in which the pinion 30 and gear 31 are disengaged, as shown in Fig. 17.

Fixedly mounted on a collar 51 centered and rotatable on the shaft 31^a is a stop disc 45 having one tooth 46 (see Fig. 9). This disc is provided with a stud 47 to which is connected a flat coil spring 48 which is also connected at the other end with a stud 49 on the main gear 31. This spring 48 urges stud 50 into engagement with the tooth 46, the rotation taking place when the pinion 30 is moved out of contact with the main gear 31.

The collar 51 extends through the plate 34 and dial 24 and has at the front end a thread for receiving a nut 57. Behind the nut is a disc 58 (Figs. 15 and 16) having an integral key 63, or other means, for causing the collar 51 to turn with it. This disc 58 has a handle 62 slightly bent outwardly for convenience in operating it. When the nut is loosened the stop disc 45 can be turned by the handle 62 to adjust the stop disc. It is fixed in adjusted position by screwing down the nut by a spanner not shown. When this is done the stop arm 45 is held in stationary position against the surface of the plate 34.

The hollow shaft 31^a extends through the plate 34 and the dial 24 and has at its outer end a flattened portion 52 (Fig. 1) on which is a disc 53 with an oblong opening fitting the flattened portion of the shaft. The pointer 18 is carried by the disc 53 and preferably is integral with it. Initially, to set the machine, this pointer is moved counterclockwise to the point on the circular scale that indicates the number of thousands or hundreds of yards to be wound to form each package. The turning of the pointer 18 carries the

shaft 31^a and the gear 31 with it back to the starting point.

The shaft 16 extends through and beyond the end of the shaft 31^a. At the end this shaft 16 is flattened on two sides to receive an oblong perforation in a disc 55. On this disc is an integral pointer 56 which is rigidly fixed to the shaft 16 by screwing down a nut 54 on a screw-threaded end of the shaft 16. On this pointer 56 is a knurled handle 74. The turning clockwise of the pointer 56 by the handle 74 will turn the shaft 16 and the operating disc 25 without turning the stop disc 45. This motion of the tooth 27 turns the gear 28 one tooth at each complete rotation of the pointer 56. When the pinion 30 and gear 31 are in mesh, the turning of the pointer 56 will slowly turn the pointer 18 therefore, through the shaft 31^a, for a fine adjustment in one direction only.

The tooth 46 is moved by the handle 62 into the right position without resistance from the clutch 20 so that, when the pointer 18 has turned through the proper angle to indicate the desired number of yards, the pointer 18 will come to zero, moving up to it in a clockwise direction from the point at which it was originally set. It is in this way that the device is set and the pointer 18 left free to be turned to the desired point by the winding of the yarn but capable of being moved back automatically from the zero point to the original point at which it was set, as will appear hereinafter.

The lever 32 is provided with a projection 63 which enters a notch 64 in a cam 65 pivoted on a shaft 66 carried by the extension 12 parallel to the shaft 11 (see Figs. 1 and 3). The cam is provided with an operating end 67. The shaft 11 is provided with a cam 68. In the ordinary running of the machine the end 67 of the cam 65 rides on a bearing 69 for the shaft 11 and, of course, has no motion. When the lever 32 is turned from the position shown in Fig. 11 to that shown in Fig. 17, by the engagement of the projection 32^a in the lever 32 by pin 60 on the gear 31, the end 67 is thrown to the end of the shaft 11 where it rides on the cam 68. The next turn of the cam 68 will move the end 67 and turn the shaft 66. This shaft 66 has on the outside of the extension 12 an arm 70 which is connected with a stop motion for the winding machine to stop that machine and leave the spindle on which the yarn is being wound stationary. This gives the operator a chance to change the bobbin or cop and replace it by a new one, winding the yarn around the pulley 10.

Just before stopping when the pinion 30 is disengaged from the gear 31 the spring 48 turns the gear 31 back to the original position to which it was set. This also turns the pointer 18 back to its original position in the scale. The pointer 56, having been turned back by hand to zero, the tooth 27 is brought thereby to a position close to the arm 44. Now the winding machine is started and the shaft 11 starts by the action of the yarn. Immediately thereafter the tooth 27 comes into contact with the arm 44 and forces the lever 32 back toward the gear 31 and the teeth of the pinion 30 into the teeth of the gear. The spring-pressed pawl 37 goes back with the gear 28 and keeps that gear from rotating more than one tooth at an operation.

In the operation of the device, the operator, by means of the handle 62 and after loosening the nut 57, turns the collar 51 and sets the pointer 18 at the desired point, as for example, 4, on the

scale. This point may represent a winding of 4,000 yards. Then the winding machine is started by any ordinary means and the process above described takes place, the pointer 18 moving gradually clockwise around the scale to zero. 5 When zero is reached the machine is stopped automatically by the stud 60 engaging the projection 32^a on the lever 32 and carrying the pinion 30 out of mesh. Now the package of wound yarn is removed, when all operation is suspended, 10 and an empty spool placed on the winding machine and threaded over the pulley 10. Then by the spring 48 the pointer 18 is automatically moved back to the number 4 and the process starts over again. 15

In this way the machine can be once set to the number 4, or any other number, and it will automatically wind off bobbins with four thousand yards of yarn or thread repeatedly so long as it is desired to produce packages of that size with 20 the operator only changing bobbins and starting the winding machine.

When it is desired to produce packages of another size, a wrench, not shown, is applied to the nut 57 and then the handle 62 is turned to 25 turn the collar 51 and stop 46. At the same time the spring 48 rotates the gear 31 automatically to separate the stop far enough from the tooth 46 to accomplish this adjustment. When it is desired to turn the shaft 16 for fine adjustments, 30 that is done by the handle 74, as has been stated. In this way the objects of this invention are secured and a measuring machine is provided which is simplified and the cost of which is reduced. 35

Having thus described my invention and the advantages thereof, I do not wish to be limited to the details herein disclosed, otherwise than as set forth in the claims, but what I claim is:

1. In a measuring machine, the combination 40 of a main shaft, a gear rotatably mounted thereon a stop disc centered on the main shaft, yielding means for connecting the stop disc and gear to normally urge the gear into a predetermined position with respect to said stop disc, means for 45 fixing the stop disc in stationary position to fix the stopping point for the gear, and means whereby the loosening of said means will permit the adjustment of the disc.

2. In a measuring machine, the combination of 50 a main shaft, a gear rotatably mounted thereon and having an eccentric pin, a stop disc centered on the main shaft and having an eccentric pin, a coil spring connecting said pins to urge the gear into predetermined position with respect to 55 the stop disc, and means for fixing the disc in stationary position to adjust and fix the zero point for the gear.

3. In a measuring device for yarn and the like, the combination of an operating disc, means for 60 rotating the disc by the motion of the yarn or the like being measured, a tooth on the disc, a gear rotatable on the same axis as the disc, disconnectable means operated by the tooth for rotating said gear, a pointer rotatable with the 65 gear, a circular scale over which the pointer moves, and means operated by the gear to disconnect said disconnectable means to render the tooth inoperative to drive the gear and temporarily leave the gear disconnected from its operating mechanism. 70

4. In a measuring machine, the combination with a pulley adapted to be operated by the yarn or the like being measured, a central shaft, an operating disc concentric with the shaft and ro- 75

- 5 tatable therewith, a gear concentric with the shaft but rotatable freely thereon, a pivoted lever having means adapted to be operated by said disc once during each rotation of the operating disc 5 for rotating said gear intermittently, and a pin on the gear in position to engage the lever to swing it so that said operating means is disconnected so that the gear is free from its operating means.
- 10 5. In a measuring machine, the combination with a pulley over which the material to be measured passes to turn the pulley, a shaft, means for turning the shaft by the rotation of said pulley, an operating disc fixed to said shaft, a gear loose 10 on said shaft, a pivoted lever and a pair of pinions fixed together and rotatably mounted on said lever, one pinion meshing with said gear, said operating disc having a tooth which, on each revolution, engages the other pinion to turn it.
- 15 6. In a measuring machine, the combination with a pulley over which the material to be measured passes to turn the pulley, a shaft, means for turning the shaft by the rotation of said pulley, an operating disc fixed to said shaft, a gear loose 15 on said shaft, a pivoted lever, pinion rotatably supported on said lever and meshing with said gear, said operating disc having a tooth which, on each revolution, turns the gear one step, a scale, and a pointer fixed to be turned 20 by said gear over the scale.
- 20 7. In a measuring machine, the combination with a pulley over which the material to be measured passes to turn the pulley, a shaft to which the pulley is fixed, said shaft having a worm, 20 a worm wheel meshing with the worm, a friction clutch carried by said worm wheel, a gear in a plane parallel to the worm wheel, an operating disc connected with the clutch to be turned thereby in one direction only, a pivoted lever, a shaft 25 carried by the lever, two pinions fixed to the last named shaft, one adapted to mesh with said gear, said operating disc having a tooth which, on each revolution, engages the other pinion and turns it the space of one tooth to turn the gear through 30 an equal space, a scale, and a pointer fixed to turn over the scale with the gear.
- 25 8. In a measuring machine, the combination with a pulley over which the material to be measured passes to turn the pulley, a shaft, means for turning the shaft by the rotation of said pulley, an operating disc fixed to said shaft, a gear loose 30 on said shaft, a pivoted lever, a pair of pinions fixed together and rotatably mounted on said lever, one pinion meshing with said gear, said operating disc having a tooth which, on each 35 revolution engages the other pinion to turn it and the gear, a scale, a pointer fixed to be turned by said gear over the scale, and a second pointer fixed to said shaft and having a handle to turn the shaft for fine adjustment.
- 35 9. In a measuring machine, the combination of an operating disc, a gear mounted to turn on the same axis as the operating disc, a pivoted lever, two connected pinions rotatably supported by the lever, one meshing with said gear and the other adapted to be moved intermittently by the rotation of said operating disc, the lever having two notches, a second pivoted lever having one tooth for engaging in either of the notches to hold the pinion and gear in or out of engagement, a pin on the gear for engaging an arm on the lever and throwing the pinions outwardly out of engagement, means carried by said disc for engaging said arm to swing the lever back to mesh the pinion and gear, a spring for forcing the lever with one tooth into operative position, and a spring for holding one of said gears by its tooth so as to prevent its operating more than one step at a time, an arm on the lever having a pin, an oscillatable shaft, a pivoted cam on said shaft having a notch re-
- 40 75

with one tooth into operative position, and a spring for holding one of said gears by its tooth so as to prevent its operating more than one step at a time.

10. In a measuring machine, the combination 5 of a rotary operating disc, a gear mounted to turn on the same axis as the operating disc, a pivoted lever, two connected pinions rotatably supported by the lever, one meshing with said gear and the other adapted to be moved intermittently by 10 the rotation of said operating disc, the lever having two notches, a second pivoted lever having a tooth for engaging in either of the notches to hold the pinion and gear in or out of engagement and yieldingly holding the other lever, a pin on the 15 gear for engaging an arm on the lever and throwing the pinions outwardly out of engagement, means carried by said disc for engaging said arm to swing the lever back to mesh the pinion and gear, and a spring having a pawl for holding one 20 of said gears by the space between two teeth so as to prevent its operating more than one step at a time, a stationary stop disc having a tooth, a stop stud on the gear in position to engage the tooth on the stop disc and position the gear 25 for winding a predetermined length of yarn, or the like.

11. In a measuring machine, the combination of an operating disc, means for rotating the operating disc, a gear mounted to turn on the same 30 axis as the operating disc, a pivoted lever, two connected pinions rotatably supported by the lever, one meshing with said gear and the other adapted to be moved intermittently by the rotation of said operating disc, the lever having 35 two notches, a second pivoted lever having a tooth for engaging in either of the notches to hold the pinion and gear in or out of engagement, a pin on the gear for engaging an arm on the lever and throwing the pinions outwardly 40 out of engagement, means carried by said disc to swing the lever back to mesh the pinion and gear, a spring for forcing the lever with one tooth into operative position, a spring having an end for holding one of said gears by its tooth so as to prevent its operating more than one step at a 45 time, a stop disc having a tooth adapted to be set in stationary position when adjusted for length of yarn to be wound, a stop stud on the gear in position to engage the tooth on the stop disc when the gear is rotated through the angle 50 for which the tooth is set and stop the gear, and a spring connecting the stop disc and gear at opposite ends to form a yielding connection between them.

12. In a measuring machine, the combination 55 of an operating disc, a gear mounted to turn on the same axis as the operating disc, a pivoted lever, two connected pinions rotatably supported by the lever, one meshing with said gear and the other adapted to be moved intermittently by the 60 rotation of said operating disc, the lever having two notches, a second pivoted lever having one tooth for engaging in either of the notches to hold the pinion and gear in or out of engagement, a pin on the gear for engaging an arm on the lever and throwing the pinions outwardly out of engagement, means for engaging said arm to swing the lever back to mesh the pinion and gear, a spring for forcing the lever with one tooth 65 into operative position, and a spring for holding one of said gears by its tooth so as to prevent its operating more than one step at a time, an arm on the lever having a pin, an oscillatable shaft, a pivoted cam on said shaft having a notch re- 70

75

ceiving said pin, a shaft parallel to the oscillatable shaft through which the machine is run, a cam on the last named shaft in contact with which the said first named cam is moved by the operation of said arm on the lever, and stopping connections carried by the oscillating shaft and adapted to stop a winding machine when the shaft is oscillated by the cam mounted thereon.

13. In a measuring machine, the combination of an operating disc, a gear mounted to turn on the same axis as the operating disc, a pivoted lever, two connected pinions rotatably supported by the lever, one meshing with said gear, when the lever is in one adjusted position, and the other adapted to be moved by the rotation of said operating disc, a pin on the gear for engaging an arm on the lever to throw the pinion out of engagement with the gear, means on the disc engaging said arm and swinging the lever back into operative position, a pin carried by the lever, an oscillatable shaft, a pivoted cam on said shaft having a notch receiving said pin, a shaft parallel to the oscillatable shaft through which the machine is run, a cam on the last named shaft in contact with which the said first named cam is moved by the operation of said pin on the lever, and stopping connections carried by the oscillating shaft and adapted to stop a winding machine when the shaft is oscillated by the cam mounted thereon.

14. In a measuring machine, the combination of a main shaft, an operating disc, a gear mounted to turn on the same axis as the operating disc, a pivoted lever, two connected pinions rotatably supported by the lever, one meshing with said gear and the other adapted to be moved by the rotation of said operating disc, means on the gear for pivoting the lever to throw the pinions out of operative position, the lever having an arm, means on the disc for engaging said arm and swinging the lever back into operative position, a pin carried by the lever, an oscillatable shaft, a pivoted cam on said shaft having a notch receiving said pin, and a cam on the first named shaft in contact with which the said first named cam is moved by the operation of said pin on the lever.

15. In a measuring machine, the combination of an operating disc, a gear mounted to turn on the same axis as the operating disc, a pivoted lever, two connected pinions rotatably supported by the lever, one meshing with said gear and the

other adapted to be moved intermittently by the rotation of said operating disc, a pin on the gear for engaging a projection on the lever and throwing the pinions out of engagement, means on the disc for engaging an arm on the lever to swing the lever back to mesh the pinion and gear, and a spring for holding one of said gears by its tooth so as to prevent its operating more than one step at a time.

16. In a measuring device for yarn and the like, the combination of an operating device, means for rotating the operating device by the motion of the yarn or the like being wound, a gear rotatable on the same axis as the operating device, disconnectable means operated by said device for rotating said gear, a pointer rotatable with the gear, a circular scale over which the pointer moves, means carried by the gear for operating the disconnectable means to disconnect the device from the gear, means operated by the disconnectable means for stopping the winding operation, means for first moving the pointer and gear back on the scale automatically to its original position when the winding operation is stopped, and means operated by the return of the gear to initial position for then automatically operating the disconnectable means to again connect the gear with its operating means.

17. In a measuring machine, the combination of a main shaft, a gear rotatably mounted thereon, an adjustable stop device centered on the main shaft, a stud on the gear, yielding means for connecting the stop device and stud to normally urge the stud on the gear into contact with said stop device, a fixed front plate, a tubular shaft on the main shaft fixed to the stop device and screwthreaded at its outer end, and a nut on the screwthreads for fixing the stop device against the inner surface of said plate.

18. In a measuring device for yarn and the like, the combination of an operating disc, means for rotating the disc by the motion of the yarn or the like being measured, a gear rotatable on the same axis as the disc, disconnectable means for rotating the gear step by step by the rotation of the disc, a pointer rotatable with the gear, a circular scale, and means operated by the gear for disconnecting said disconnectable means and thereby stopping the rotation of the gear when the pointer reaches the zero point on the scale.

JOHN A. ADELL.
